OSCILLATING MOTOR FOR HIGHWAY
CROSSING SIGNALS

Alfred F. Meuler, Milwaukee, Wis.

Application March 7, 1951, Serial No. 214,236

1 Claim. (Cl. 310—39)

1

This invention appertains to railroad highway crossing signals of the type embodying a swinging banner or signal plate actuated by electromagnets upon the closing of circuits thereto through the entrance of a train into a signal block.

Such signals embody a pair of electromagnets mounted on the upper end of the movable rod carrying the banner and a stationary electromagnet on the frame of the signal above the rod. By means of a circuit selector, energy is applied alternately to the magnet coils, so as to cause the stationary and one of the moving coils to attract each other, bringing about the swinging of the rod and banner. Much difficulty has been experienced with the circuit selector now in common use, and all circuit selectors with which I am familiar embody a cam movable with the banner for actuating a switch lever carrying leaf spring contacts. With this type of selector, delicate adjustments are necessary and arcing between contacts makes frequent inspection necessary as well as frequent replacement of parts.

One of the primary objects of my invention is the provision of a novel circuit selector, which will effectively accomplish the purpose intended, and which will entirely eliminate the use of an operating cam, switch lever, resilient contacts, etc., so that the number of moving parts is reduced to a minimum, whereby frequent inspection of the signal and the replacement of worn parts is unnecessary.

Another salient object of my invention is the provision of a single switch panel mounted on the rock shaft of the banner arm for movement therewith, carrying novelly arranged mercury switches for controlling the circuits to the magnets.

A further important object of my invention is to provide a highway crossing signal of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described and claimed, and illustrated in the accompanying drawing, in which drawing,

Figure 1 is a detail fragmentary vertical sectional view through a highway crossing signal embodying my novel circuit selector, the section being taken on the line 1—1 of Figure 2, looking in the direction of the arrows.

2

Figure 2 is a detail sectional view taken at right angles to Figure 1, and on the line 2—2 of Figure 1, looking in the direction of the arrows.

Referring to the drawing in detail, wherein similar reference characters designate corresponding parts throughout the several views, the letter S generally indicates a railroad highway crossing signal, and the same includes a casing having a bottom supporting plate 5. Only a fragment of the casing is shown, and it is to be understood that the same is rigidly carried by a supporting post and arm at a highway crossing. Rigidly secured to the plate 5, are a pair of spaced bearing brackets 6, and these brackets support for rocking movement the signal rock shaft 7. Rigidly secured to the rock shaft 7, by means of a Y-shaped yoke 8, is the banner rod 9. The banner rod 9 extends through a suitable slot in the wall 5, so that the rod can move back and forth with the cross shaft. The rod 9, carries the desired type of signal banner 10. The yoke 8 includes diverging legs on which are mounted the electromagnets 11 and 12. The magnets 11 and 12 are arranged at an acute angle relative to one another and lie, normally, on opposite sides of the vertical. As these magnets 11 and 12 move with the banner rod 9, the same will be referred to hereafter as the moving magnets. Forming a part of the frame of the signal, are uprights 13 connected at their upper ends by a cross bar 14. The cross bar has rigidly secured thereto a depending stationary electromagnet 15. The magnet 15 is located directly above the rock shaft 7 and the banner rod 9, and under normal conditions, the magnet 15 is between the magnets 11 and 12. In accordance with my invention, I secure to the rock shaft 7 for movement therewith a panel 16 which constitutes a part of my circuit selector for the magnets. This panel 16, can be formed from dielectric material and resilient clips 17 are secured to the panel for detachably receiving mercury switches 18, 19, 20 and 21. Each mercury switch, is of the type embodying a sealed tube or bulb 22, containing a quantity of mercury 23, and spaced contacts 24. The contacts 24 are located adjacent to one end of the closed tube or bulb, so that when the bulb is in one position relative to the horizontal, the mercury will flow toward and over the contacts to bridge the same, and when the tube or bulb is at an opposite angle to the horizontal, the mercury will flow to the other end of the tube or bulb, away from the contacts. It is to be noted that in my arrangement, all of the closed tubes or bulbs are tilted in one and the same direction, when the panel 16 is in a vertical position. The

mercury switches are used in pairs and hence the switches 18 and 19 have their contacts 24 located at the left hand side of the bulbs, (see Figure 1), and the switches 21 and 20, have their contacts located at the right hand side of the bulbs. In the position shown in Figure 1, the contacts 24, for the switches 18 and 19 are bridged by the mercury, while the contacts for the switches 20 and 21 are above the mercury.

Now referring to the wiring for the signal, 10 which has been shown diagrammatically in Figure 1, the same includes conductor wires 25 and 26 leading from a suitable source of electrical energy (direct current). Interposed in the wire 26 is the circuit closer 27, and this circuit closer is operated when a train moves into a signal block and it is again to be noted that this is merely a diagrammatic showing. The wire 26 is connected directly to one contact of the mercury switch 18, and the other contact of this switch has electrically connected therewith a wire 28 which is electrically connected with one terminal of the magnetic coil of the electromagnet 11. The other terminal of this coil has electrically connected therewith, a branch wire 29, which is electrically connected with the main wire 25. Electrically connected with the main wire 26 is a branch wire 30, and this wire is electrically connected with one contact of the mercury switch 19 and the other contact of this switch has electrically connected therewith a conductor wire 31, which is connected with one terminal of the magnetic coil of the stationary magnet 15. The other terminal of this coil is connected directly to the wire 25.

Leading from the main wire 25 is a branch wire 32 and this wire is electrically connected with one contact of the mercury switch 20 and the other contact of this switch has electrically connected therewith a wire 33, which is electrically connected with one terminal of the magnetic coil of the electromagnet 12. The other terminal of the coil is connected by a branch wire 34 with the wire 25. Electrically connected to the wire 32 is a wire 35 and this wire is electrically connected with one contact of the switch 21 and the other contact of this switch has connected therewith a wire 36, which leads to and is connected with the wire 31, which in turn is connected with one terminal of the coil of the electromagnet 15.

Now, considering that a train enters the signal block and the circuit closer 27 is moved to its closed position. Current flowing through wire 25 will enter switch 18 through the bridge contacts, through wire 28, coil of electromagnet 11 to wire 29 and to wire 25. Simultaneously with this, current will flow through wire 30, through switch 19, through wire 31 through the coil of the electromagnet 15, back to wire 25. Consequently, electromagnets 11 and 15 will be energized and will attract one another, and the magnet 11 will be moved to the right, see Figure 1, bringing about the rocking of the shaft 7, and the swinging of the banner to the left. As soon as the magnet 11 is in vertical alignment with the magnet 15, the mercury switches will all be tilted in the opposite direction from that shown in Figure 1, and consequently, the contacts of switches 20 and 21 will be bridged and the mercury will move

away from the contacts of switches 18 and 19 and the banner 10 will start to swing to a lower, vertical position by gravity. Also at this time, magnets 12 and 15 will be energized, as follows: 5 Current will flow through wire 26 and wire 32 through mercury switch 20, through electromagnet 12, through wire 34, back to wire 25. Current will also flow through wires 32 and 35, through the switch 21, wires 36 and 31 through the electromagnet 15, back to wire 25. The energizing of the magnets 12 and 15 will cause movement of the magnet 12 into vertical alignment with the magnet 15, bringing about the swinging of the banner to the right. The mercury in the switches 15 will immediately flow to the opposite ends of their closed tubes or bulbs, bringing about the breaking of the circuits through the magnets 12 and 15, and again bringing about the energizing of the magnets 11 and 15. Consequently, swinging 20 of the banner will continue as long as the circuit closer 27 is in its closed position.

For the sake of simplicity, circuits have only been shown for the operating magnets, and it is to be understood that the highway signal is to 25 be equipped with the ordinary adjuncts, such as audible signals, visual signal lights, etc.

From the foregoing description, it can be seen that I have provided an exceptionally simple and durable form of circuit selector for highway 30 crossing and like signals.

Changes in details may be made without departing from the spirit or the scope of this invention, but what I claim as new is:

In a highway crossing signal for railroads, 35 a frame, a rock shaft supported by the frame, a stationary magnet on the frame arranged above the rock shaft, a pair of movable magnets carried by the rock shaft arranged in diverging relation and normally disposed on opposite sides of the 40 stationary magnet, and a circuit selector for the magnets including a panel rigidly secured to the rock shaft for movement therewith, a pair of mercury switches secured to the panel electrically connected respectively to the stationary 45 magnet and to one movable magnet, a second pair of mercury switches electrically connected respectively to the stationary magnet and to the other of the movable magnets, the contacts for the first pair of mercury switches being disposed 50 at one end thereof and the contacts for the second pair of switches being located at the opposite end thereof, said mercury switches being all tilted in the same direction on the panel with the contacts of one pair of switches bridged 55 when the panel is in a vertical position.

ALFRED F. MEULER.
